Inventor:-

John Angel

UNITED STATES PATENT OFFICE

2,276,365

ROTARY CUTTING DEVICE

John Angel, Detroit, Mich.

Application September 26, 1939, Serial No. 296,618

3 Claims. (Cl. 30—240)

My invention relates to rotary cutting devices, and its principal object is to provide a device of the character referred to which is adapted for cutting all kinds of sheet material such as paper, cloth, leather and so forth, and more particularly for cutting asbestos sheeting of the kind used in the roofing and siding of buildings. This latter material presents peculiar difficulties due to the fact that it is saturated with asphalt or similarly sticky material and also that it is coated upon one side with a layer of crushed stone or other abrasive material.

An essential feature of my said invention therefore, in order to meet the above requirements, resides in the combination of a pair of co-acting rotary cutters, the upper of which is provided with a relatively obtuse cutting edge, while the lower one has a very acute cutting edge, the upper cutter being operated in contact with the abrasively coated side of the material while the lower or sharper cutter operates upon the soft, sticky portion of the material.

Another object of my invention is to provide means for continuously cleaning and lubricating the lower and sharp-edged cutter during its operation.

Another object of my invention is to provide a rotary cutting device, the frame of which is so disposed as to permit it to pass easily between the adjacent edges of the cut.

A further object of my said invention is to provide simple and effective means for adjusting the distance between the centers of the co-acting cutters so as to provide for wear of the same and reduction of diameter due to frequent sharpening of the cutting edges.

With these and other objects in view, I will now describe a preferred embodiments of my invention, reference being had to the accompanying drawing, in which—

Figure 1 is a side elevation of my improved device.

Figure 2 is a plan view of the same.

Figure 3 is a vertical section taken on line 3—3 of Figure 1.

Figure 4 is a vertical section taken on line 4—4 of Figure 1, and

Figure 5 is an end elevation taken on line 5—5 of Figure 1.

Like characters designate corresponding parts throughout the several views.

In the drawing, 1 designates the metal stem of the device provided at its upper end with a handle 2 of wood or other suitable material, and having its lower end bifurcated as indicated by lines *a*, *b*,

5 to provide a pair of arms 3, 4 upon the extremities of which are mounted the cutters or knives 5, 6, respectively, the said arms being arranged in laterally offset relation as will be seen from Figure 3, so that the working edges of the cutters are brought into proper alignment.

Thus, as shown more clearly in Figure 3, the upper cutter 5, having a relatively obtuse cutting edge 51, is provided with integral bosses 52 bored to receive the ball bearing 53, the inner race of which is mounted upon a stud 7, the said stud having a reduced portion 71 which fits tightly in an opening in the arm 3 and is secured in position by the nut 72. Similarly, the cutter 6, having an acute edge 61, is provided with integral bosses 62 bored to receive the ball bearing 63, the inner race of which is mounted upon a stud 8, the said stud having a reduced portion 81 which fits tightly in an opening in the arm 4 and is secured in position by the nut 82. It will be observed that the main body of the stud 7 is disposed eccentrically in relation to the reduced portion 71 thereof, so that by rotating it in the opening in the arm 3, the distance between the centers of the co-acting cutters 5 and 6 may be varied, as before stated.

It will be observed by reference to the sections Figures 3 and 4 that between the arms 3 and 4 the metal is cut away so as to provide a valley, marked V on the drawing, extending in general along the line *x*—*x* of Figure 1 so that, due to the reduced thickness of the body along this line, the force requisite to propel the cutter along the slit being formed is reduced to a minimum. Below 30 the cutter 6 is a guard member 9 secured to the main body as by screw 91, this guard serving to support the device as a whole and to protect the edge of the cutter.

In order to prevent accumulation of asphalt or other sticky substance in the material to be operated upon, there is provided a pad 10 or felt or other absorbent material which is held in the lower forked end of a tubular member 101, the upper end of which is provided with a reservoir 103, soldered to the body as at B1 and adapted to contain kerosene or other solvent or cleansing liquid and feed it to the pad 10, the rate of feed being determined by a knob 104 formed integral with a stem 105 which projects downwards through the reservoir 103 and terminates in a needle valve of any conventional construction so well known that it is unnecessary to describe it further.

In cutting roofing material by a device of the present character some difficulty is found in the

fact that the sheet of material assumes an undulatory form, making it difficult to run the cutters with exactness along the desired line. In order to obviate this difficulty I have provided in advance of the cutters 5 and 6 an upper roller 12 having a relatively wide surface and a lower roller 13 having a narrow surface, as shown more clearly in Figure 5 of the drawing. The roller 12 is mounted upon a pin 120 in a swinging arm 121 pivoted at 122 to the frame and pressed downwards by an arcuate spring 123, while the lower roller 13 is carried upon a fixed screw 130 as shown in Figures 1 and 5.

While I have herein described and shown a preferred embodiment of my invention, it will be readily understood by those skilled in the art to which the same relates that various modifications may be made to suit particular or peculiar requirements without departing from the spirit of my invention as defined in the appended claims.

Having thus described my said invention, what I claim and desire to secure by Letters Patent of the United States is:

1. In a device of the character described, the combination, with a body bifurcated to provide arms adapted to carry a pair of studs disposed in parallel spaced relation and a pair of circular cutters rotatably mounted upon said studs and

having their cutting edges arranged in cooperative relation, of a pair of guide rollers carried upon said arms and adapted to guide material into the path of said cutting edges.

5 2. In a device of the character described, the combination, with a body bifurcated to provide arms adapted to carry a pair of studs disposed in parallel spaced relation and a pair of circular cutters rotatably mounted upon said studs and 10 having their cutting edges arranged in cooperative relation, of a pair of guide rollers carried upon said arms and adapted to guide material into the path of said cutting edges, one of said rollers being spring-mounted.

3. In a device of the character described, the combination, with a body bifurcated to provide arms adapted to carry a pair of studs disposed in parallel spaced relation and a pair of circular cutters rotatably mounted upon said studs and 20 having their cutting edges arranged in cooperative relation, of a fixed stud upon the lower of said arms carrying a roller, a lever swingably mounted upon the upper of said arms, a stud upon the free end of said lever, a roller upon 25 said stud, and spring means adapted to yieldingly urge said last mentioned roller towards said first mentioned roller, whereby the material to be cut is directed towards said cutters.

JOHN ANGEL.
